UNITED STATES PATENT OFFICE.

JOHN PRICE, OF TYLER, TEXAS, ASSIGNOR OF ONE-HALF TO ABRAM SCHEUER, OF TYLER, TEXAS.

DOOR-FASTENER.

1,250,653.

Specification of Letters Patent. Patented Dec. 18, 1917.

Application filed June 12, 1917. Serial No. 174,326.

To all whom it may concern:

Be it known that I, JOHN PRICE, a citizen of the United States, residing at Tyler, in the county of Smith and State of Texas, have invented a new and useful Door-Fastener, of which the following is a specification.

The invention relates to a door locking device, and more particularly to the class 10 of portable door fasteners.

The primary object of the invention is the provision of a fastener of this character, which when not in use will have its parts interfitted to render the same compact, so 15 that it may be conveniently carried in the pocket and, on the application thereof, will securely hold a door against opening movement, thereby firmly sustaining said door closed.

20 Another object of the invention is the provision of a fastener of this character wherein the construction thereof is novel in form to assure the easy application and securing of a door closed with despatch; possessing 25 minimum parts, which are readily interfitted to render it portable, and for the fastening of the door when the occasion requires; thoroughly reliable and efficient in its purpose, strong, durable and inexpensive 30 in manufacture.

With these and other objects in view, the invention consists in the features of construction, combination and arrangement of parts, as will be hereinafter fully described, 35 illustrated in the accompanying drawings, and pointed out in the claim hereunto appended.

In the accompanying drawing:

Figure 1 is a fragmentary horizontal sectional view through a door casing and door showing the fastener constructed in accordance with the invention applied for securing the door closed.

Fig. 2 is a plan view of the claw or jaw member, showing the locking key in sectional elevation.

Fig. 3 is a perspective view of the fastener in position to be carried in the pocket.

Fig. 4 is a sectional view on the line 4—4 50 of Fig. 3, looking in the direction of the arrow.

Similar reference characters indicate like parts throughout the several figures.

Referring to the drawing in detail, the 55 portable fastener comprises only two sec-

tions, one constituting the claw or jaw member A, and the other the locking key B therefor. The member A is formed from a flat plate, preferably metal, cut or shaped to provide a narrow shank 5 and a wide 60 head 6, which has extending at right angles from one side thereof a plurality of pointed teeth 7, which are arranged in a row at the end edge of said head, affording a claw or jaw for a purpose presently described. 65

The shank or stem 5 has bent or formed, at its longer opposite side edges, outwardly and inwardly bent flanges 8, which provide guide and retaining cleats for a locking key hereinafter fully described. 70

The locking key comprises a straight bar 9 of the required length, width and thickness and is formed in its opposite longer side edges with V-shaped grooves or channels 10 for receiving the cleats 8 when the 75 key B is fitted upon the member A in parallel relation thereto by the sliding of the bar 9 longitudinally of the member A between the flanges 8 in the direction of the teeth 7 for assuming the position shown in Fig. 3 80 of the drawings, so that the fastener has its sections interfitted for the convenient carriage thereof in a pocket when the fastener is not in use, as the sections of the fastener in such position are compact to 85 occupy the least possible space.

The bar 9 constituting the locking key B of the fastener, when disengaged from the flanges 8 on the member A, is adapted to fit in the head 6 of said member, which head is 90 provided medially thereof at the required distance from the teeth 7 with a slot or opening 11 correspondingly shaped to the cross sectional contour of the bar 9 for slidably receiving the same, so that the key B may 95 be positioned at right angles to the member A when the fastener is assembled and applied for securing a door closed.

In the application of the fastener, the key B is separated from the member A, it 100 being assumed that the door C is open, so that the head 6 of the member A can be inserted in the rabbet in the casing D for the door, as shown in Fig. 1 of the drawings, and when the door is moved to closed position, it rides upon the member A, forcing the teeth 7 into the casing D and when the door has been completely closed, the key B is inserted through the head 6 of the member A transversely thereof to lie crosswise 110

of the door C and casing D at the inner sides thereof, so as to securely lock the door closed, as clearly shown in Fig. 1 of the drawings.

The fastener affords a convenient securing device for doors to prevent the same from being opened from without, and the application of the fastener is not restricted to use with doors, but may be applied to transoms or other closures.

10 It is, of course, understood that changes, variations and modifications may be made in the fastener, such as come properly within the scope of the appended claim, without departing from the spirit of the invention or sacrificing any of its advantages.

What is claimed is:—

15 A door fastener, comprising a flat member formed with a narrow shank and a wide head constituting a jaw, a plurality of teeth 20 projecting parallel from the free end edge of the head at substantially right angles thereto, substantially V-shaped cleats on the

shank at one side thereof lengthwise of the same, and a locking key formed from a straight bar of a slightly greater thickness 25 than the flat bar having in opposite edges grooves corresponding to the cleats to receive the same when the key is passed between said cleats for the fastening thereof parallel with and at one side of the shank, 30 said head being formed with a slot correspondingly shaped to the cross sectional shape of the key for receiving the same on disengaging it from the cleats, the thickness of the fastener being the combined thickness 35 of the flat bar and key.

In testimony, that I claim the foregoing as my own, I have hereto affixed my signature in the presence of two witnesses.

JOHN PRICE.
